UNITED STATES PATENT OFFICE.

EDWARD MURPHY, OF CLE ELUM, WASHINGTON.

ORE-SAMPLE GRINDER.

Application filed July 2, 1923. Serial No. 649,115.

To all whom it may concern:

Be it known that I, EDWARD MURPHY, a citizen of the United States, residing at Cle Elum, in the county of Kittitas and State of Washington, have invented certain new and useful Improvements in Ore-Sample Grinders, of which the following is a specification.

This invention relates to improvements in means for grinding ore.

The primary object of this invention is the provision of a relatively simple, compact and very efficient type of device, which may be used in connection with the grinding of ore for obtaining samples.

A further object of this invention is the provision of an ore grinder of the above mentioned character which embodies an ore container having means therein for effectively operating directly upon ore aggregate as to most effectively grind the same or pass the same in a substantially pulverized condition to a desired location.

Other objects and advantages of this invention will be apparent during the course of the following detailed description.

In the accompanying drawing, forming a part of this specification, and wherein similar reference characters designate corresponding parts throughout the several views.

Figure 1 is a side elevation of the improved ore sample grinder.

Figure 2 is an elevation of the improved container used in connection with the grinder, taken substantially at right angles to the view illustrated in Figure 1.

Figure 3 is a cross sectional view, taken through the improved grinder substantially on the line 3-3 of Figure 1, showing improved details of the grinder.

Figure 4 is a transverse cross sectional view, taken substantially on the line 4-4 of Figure 2, thru the container of the improved grinder.

In the drawing, wherein for the purpose of illustration is shown but the preferred embodiment of this invention, the letter A may generally designate the improved grinder, which may include a supporting frame B, a container F, and a collecting pan or receptacle H.

Referring to the frame B, the same preferably includes a pair of side standards 10 and 11, which may be of identical formation,

either cast or stamped of sheet metal, including the upstanding portions 12 which may be substantially rectangular in formation and provided with slots 13 inwardly of their upper ends. At their lower ends, the body portions 12 have integral therewith the base flanges 14 of each of the standards 10 and 11 which are outturned at right angles thereto, and provided with suitable transverse openings for receiving securing elements 15, such as nails, whereby the frame B may be assembled upon a block or other support K. As it is desired to space the standards 10 and 11 for a predetermined distance, straps 17 and 18, may be provided, extending transversely from the standard 10 to the standard 11, and suitably welded to said standards, substantially as is illustrated in the drawing.

The body portions 12 of the standards 10 and 11 may be suitably apertured, slotted, or provided with open work to reduce the weight of the same, without sacrificing any reinforcing feature which the same is adapted to perform in its support of the container F.

Referring to the container F, the same is preferably of cylindrical formation including the cylindrical shaped body portion 20, which is entirely open at both ends, and exteriorly screw threaded at said ends for detachably receiving imperforate caps 21 and 22. Bearing spindles 23 and 24 are secured to the container F, intermediate the caps 21 and 22, at diametrically opposed points upon said container, said spindles 23 and 24 being adapted to rest in the notches 13 of the standards 10 and 11 to support the container F for rotation on an axis disposed transversely at right angles to the normal longitudinal axis of the cylindrical container F.

The spindles 23 and 24, just inside of the standards 10 and 11 preferably have spacing washers 26 and 27 respectively provided thereon, which are adapted for contact with the inside surfaces of the standards 10 and 11 respectively to space the container F intermediate said standards against liability of engagement therewith. The spindle 23 may extend outwardly from its standard 10, and have thereon a drive pulley 30 of any approved type, so that the container F may be moved by a power unit (not shown). The opposite spindle 24 may extend outwardly of its standard 11 and pref-

erably has a crank handle 33 thereon for manual movement of the container F upon its rotation axis.

- 5 In a side of the container F, offset with respect to the axis of rotation of the container F, an opening 38 is provided in the body portion 20 of the container F adjacent the cap 22, the plane of the opening 38 being disposed substantially transversely of the 10 plane in which the container F rotates. The opening 38 is substantially polygonal shaped, and exteriorly upon the body 20 of the container F a substantially U-shaped retaining flange 40 is provided, for slidably 15 receiving a detachable screen structure 41, which is adapted for covering the opening 38 and thru which ore pulverized within the container F will pass into the collecting pan or receptacle H.
- 20 The receptacle or collector pan H may be of any approved construction and is adapted for positioning intermediate the standards 10 and 11, being of sufficient length so that the container F may dip 25 downwardly therein during rotation of the same; the collector pan H being entirely open at its top so that the ground ore may pass from the container F thru the screen 41 into the compartment 43 of said pan H.
- 30 Referring to the means for grinding of the ore within the container F during movement thereof, it is preferred to provide a pair of solid steel discs 45 and 46, intermediate which a body of ore 47 may be 35 placed at any desired aggregate. The discs 45 and 46 are of less diameter than the diameter of the container F within which they operate, so that it is possible that some ore 47 may pass said discs to be disposed intermediate the discs and their adjacent container caps 21 and 22.

Referring to the operation of this invention, the container F is mounted upon the frame B substantially as above described, 45 and one of the caps 21 or 22 is placed upon the container. Assuming that the cap 22 is placed upon the container, it is disposed lowermost and a disc 46 is placed within the body 20 of the container F, and upon this 50 disc a body of ore 47 is placed, substantially as illustrated in Figure 3 of the drawing. The other steel disc 45 is then placed upon the body of ore 47, and the cap 21 is placed upon the body 20 of the container F to seal 55 the discs and the body of ore within the container F. The container F is then power operated for rotation thereof or manually rotated by means of the crank 33. Frictional pounding of the ore between the discs 60 45 and 46 and intermediate the end caps 21 and 22 of the container F will, of course, tend to pulverize or grind the body of ore 47 until the same is of a consistency suffi-

cient to pass the screen 41. As the container F is rotated upon its axis, as determined by the spindles 23 and 24, the ground ore passing the screen 41 falls within the compartment 43 of the collecting pan H.

From the foregoing description of this invention, it is apparent that an ore grinding device has been provided, which is relatively simple in construction, and which yet embodies means to very effectively grind the ore for the purpose desired.

Various changes in the shape, size and arrangement of parts may be made to the form of invention herein shown and described, without departing from the spirit of the invention or scope of the claims.

I claim:

1. An ore grinder comprising a cylindrical shaped container, means mounting said container for rotation on an axis transversely of its cylinder axis, and grinding discs loosely mounted in said container and of slightly less diameter than the casing and adapted to perform a grinding action upon ore disposed in the casing between the discs.

2. An ore grinder comprising a cylinder including a body portion having detachable end caps thereon, discs disposed within the cylinder for movement longitudinally therein and of slightly less diameter than the cylinder, and means mounting the cylinder for movement to cause said discs to reciprocate longitudinally of the cylinder.

3. An ore grinder comprising a cylindrical container adapted to be mounted for rotary movement upon a transversely disposed axis intermediate its length, and non-perforated discs of slightly less diameter than the container loosely disposed within the end portions of the container and adapted to have movement longitudinally therein with material to be ground disposed in the container between the discs.

4. An ore grinding device comprising a container, means mounting the container for movement, discs loosely disposed within the container for movement longitudinally therein and adapted to be positioned in the end portions of the container with material to be ground positioned in the container between the discs, said container having a screened opening therein whereby ground ore may pass from the container.

5. In a device of the character described, a container adapted to have end over end movement, and a disc in said container of slightly less diameter than the container and adapted to be loosely seated upon material to be pulverized in the container, and have reciprocating movement longitudinally in the cylinder.

EDWARD MURPHY.
